United States Patent Office

Des. 223,942

Patented June 20, 1972

223,942

SNOW SLED

Richard E. Cone, Columbus, Ohio, assignor to The
Delphos Bending Company, Delphos, Ohio

Filed Mar. 2, 1971, Ser. No. 120,385

Term of patent 3½ years

Int. Cl. D12—14

U.S. Cl. D34—15

FIG. 1 is a front perspective view of a snow sled showing my new design;

FIG. 2 is a top plan view on a smaller scale;

FIG. 3 is a front elevational view of FIG. 2;

FIG. 4 is a left side elevational view of FIG. 2, the right side being a mirror image thereof;

FIG. 5 is a rear elevational view of FIG. 2.

I claim:

The ornamental design for a snow sled, substantially as shown and described.
